UNITED STATES PATENT OFFICE.

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA.

METALLIC WINDOW.

Application filed September 17, 1921, Serial No. 501,396. Renewed September 26, 1925.

My invention relates to windows, and is more especially concerned with sliding metallic windows such as are widely used in modern fire-proof buildings. Though my invention is otherwise applicable to some extent, various objects and advantages of the invention are generally much promoted and enhanced by sheet-metal construction.

More specifically, I aim to make the window proof against entrance of flames, as well as against ignition, tight against weather and drafts, and of neat and pleasing appearance, without unsightly exposure of sash cords or chains. I also aim to mount and 15 guide the sliding sashes in a novel and advantageous manner, and to provide for convenient and accurate adjustment of the guide means to assure easy, smooth up and down movement of the sashes, as well as proper 20 tightness around them when closed. Other advantages obtainable in connection with my invention include simplicity and ruggedness of construction; facility and general convenience in installation and use; and 25 moderate cost of manufacture.

How these and still other advantages can be secured through my invention will appear from my description hereinafter of the best forms of construction embodying the 30 invention known to me.

In the drawings, Fig. I is a front elevation (from outdoors) of a sheet-metal window conveniently embodying my invention.

Fig. II is a view at right angles to Fig. 35 I, with various parts in vertical section as indicated by the line II-II in Fig. I, certain parts being broken out and omitted for the sake of showing the rest on a larger scale than used in Fig. I.

Fig. III shows a horizontal section 40 through one of the jambs and the corresponding side rails of both sashes, taken as indicated by the line III-III in Fig. I also on a larger scale than Fig. I.

Fig. IV is a fragmentary sectional detail 45 view (similar to Fig. III, but on a larger scale) illustrating the mounting and guiding of the sash.

Fig. V shows a fragmentary vertical section 50 through one of the jambs, taken as indicated by the line V-V in Fig. III.

Fig. VI is a perspective view of one of the 55 springs shown in Figs. III and IV.

Fig. VII is a fragmentary view illustrat-

ing a modified construction of the portion 55 of the frame head or lintel with which the upper rail of the upper sash engages when the sash is closed, the view showing a vertical section corresponding to Fig. II on a larger scale.

Fig. VIII shows a horizontal section 60 through a jamb with modified construction.

Fig. IX shows a fragmentary vertical section, taken as indicated by the line IX-IX in Fig. VIII, and Fig. X is a similar view 65 with certain parts in a different position.

Fig. XI is a fragmentary view, similar to Fig. VIII illustrating still another modification.

Fig. XII is a sectional view similar to 70 Fig. IX taken as indicated by the line XII-XII in Fig. XI.

Fig. XIII is a similar view illustrating a 75 modification of the construction shown in Figs. XI and XII.

The window shown in Figs. I-VI has a frame consisting of lintel or head 1, opposed jambs 2, 2, and sill 3, all of hollow sheet metal construction. The upper and lower vertically sliding sashes 4, 5 are 80 mounted and guided on or in the window-frame by means included or enclosed in the exposed metal jamb facings 6, preferably as hereinafter described.

As shown, the lintel 1 and the sill 3 extend 85 across the ends of the jambs 2, 2, and have on their respective upper and lower surfaces outstanding embossments 7 that fit into and engage the corresponding ends of the jambs 2, 2 and thus serve to align and 90 hold the parts in definite proper relative positions from the moment when they are assembled. The parts may be securely fastened together by welding the edges of the jamb ends to the abutting upper and lower 95 sill and lintel surfaces practically all the way around. The window frame may be set and built into masonry or concrete in any suitable manner. As shown, each jamb 2 is composed of two pieces of metal, one 100 closing its inner side or belly 8 and forming its flanks 9, 9, and the other, 10, forming its outer side or back. The edge portions of the back piece 10 are bent outward and then retroverted to form grooved flanges 11 105 that fit over the flanks 9, 9 and may be spot welded on them, or the like; and these flanges 11 are engaged with the concrete or

2
mortar between and outside of them so as to anchor the window frame against displacement inward or outward. The sill 3 may be open for most of its width at its 5 lower side, so that during installation it can be filled with concrete, as shown, to make it especially firm, strong, and solid.

In the window-frame, between the jambs 2, 2, are the upper and lower vertically sliding sashes 4, 5, shown as of closely similar 10 sheet metal construction. Each rail of these sashes 4, 5 is composed of overlapping front and rear (outdoor and indoor) strips 12, 13,—the rear one 13, flat, and the front one 15 12, joggled outward at 14 to separate the strips and afford a groove or recess between them in which the edge of a glass pane 15 can be set in suitable plastic material or cement 16. As here shown, the front strips 20 12 constitute the principal structural elements of the sash, and may be appropriately mitered and welded together at the corners to form a strong, rigid frame, while the rear ones serve as removable glazing strips, 25 and are detachably secured to the front strips by means of male and female glazing screws 17.

The arrangement and mounting of the two sashes 4 and 5 on the window frame is 30 substantially the same, so that it will suffice to describe fully that of the upper sash 4 and to mark the corresponding parts of the lower sash 5 with the same reference characters.

35 Referring, then, especially to Figs. II, III, IV and V, it will be seen that the upper sash 4 has space for considerable edgewise play outside of its side rails 20, 20, between the jambs 2, 2. The front strips 12 40 which form the side rails 20 of the sash 4 have lateral flanges 22 with inward-extending portions 23, formed, as shown, by retroversion of marginal portions of said side rails. Between the retroverted margins of 45 the side rails 20 extend guides 25 that are in the present instance part of the exposed jamb facing 6, and have the form of hollow sheet metal beads. Their marginal portions 26 engage the side rail flanges 22 at their 50 inner sides or bights (i. e., away from the jamb backs 10) and thus serve to control the edgewise position of the sash 4 and limit or prevent edgewise play. The guide portions 26 are bent or turned outward (in the 55 direction of the jamb blocks 10) to extend into the retroverted side rail flange portions or retroversion-grooves 22, 23,—where they have just about enough clearance to insure 60 amply against binding,—and, on occasion, serve to control the lateral position of the sash 4 by engagement with the groove sides and limit or prevent lateral play. As shown, 65 the bends or bights forming the bottoms of the retroversion-grooves of the side rails 20 are beaded or rounded; so that besides pre-

venting or limiting edgewise play of the sash 4, the engagement of the guide portions 26 with the groove bottoms of itself ordinarily suffices to prevent or limit lateral play of the sash 4 enough to obviate contact and friction of said guide portions with the groove sides. In a word, therefore, the sash 4 is very accurately guided in its up and down movement, with minimum area of contact and friction, and yet is perfectly tight 70 and draft-proof at its side-rails.

75 For controlling the edgewise position and play of the sash 4 as mentioned above, I generally prefer to rely on engagement of the guide portions 26 with the bights or 80 bends of the side rail flanges 22, as shown, rather than on engagement of said guide portions 26 with the inner edges of the retroverted portions 23 of said flanges 22, for 85 reasons that will hereinafter become apparent.

90 The guide beads 25 here shown consist of metal strips bent to a channel or L-form corresponding to the visibly exposed portions of the rectangular beads or stops often employed in wooden windows, and they are mounted against the jamb bellies 8 so as to present the same appearance as such wooden stops. As shown, the engaging portions 26 of the guides 25 are not absolutely fixed with 95 reference to the jambs 2, 2, but are adjustable transversely of the window to control and vary the position of the sash 4 edgewise, to take up undesirable looseness or play, and to regulate the pressure on the lateral side rail flanges 22 so as to insure proper tightness under any or all conditions and minimize friction. These guide portions 26 are also adjustable in and out of the window (so to speak) to control and vary the position 100 of the side rails 20 laterally, etc. In the present instance, provision is made for effecting these adjustments concurrently, by mounting each guide 25 with a fixed fulcrum 27 for its deep front flange 28 (corresponding to the bottom stroke of the L) on the jamb 2, at the bottom of a V-shaped longitudinal groove in the belly 8 whose front wall is practically or nearly flat 105 against the flange 28 under ordinary conditions of adjustment. The engagement of the guide portions 26 with the groove bottom 22 being substantially offset, transversely of the window, inside of the fulcrum 27, rocking of the guide 25 into the window on said fulcrum will press on the side rail 20 in the direction of the jamb 2 and into the window. Screws 30 extending through the guide 25 and taking into threaded holes in stout 110 transverse metal strips 31 inside the jamb belly 8 serve as a convenient means of rocking the guide 25 in this manner, while U-shaped leaf springs 32 interposed and in compression between jamb 2 and guide 25 urge said guide the other way when the 115

screws 30 are backed out, and prevent rattling. As shown in Figs. III, IV and VI, the screws 30 extend through holes in both legs of the compression springs 32, which are mounted in the hollow guide beads 25 with their bends forward toward the flanges 28, and they are attached to the beads by rivets 33, so as to be removable with said beads.

10 By adjustment of each screw 30 to take up on the guides 25 against the resistance of the springs 32 to the proper degree, or vice-versa, the guides 25 can be rocked and adjusted with the utmost accuracy from end to end, so as to allow the sash 4 to slide up and down smoothly and easily the full height of the window, without more friction at any one point than at any other. Owing to the spring and resilience of the guide 15 strips 25, moreover, sufficient elastic flexure and tension can be created in them by taking up on the adjusting screws 30 to assure bearing contact of their portions 26 with the side-rail flanges 22 at all times without 20 excessive friction at any time,—notwithstanding variations in width of the sash 4 over the range of temperatures from zero weather to conditions of fire exposure, even.

In order to prevent excessive accumulation 25 of dust and dirt in the hollow guide-beads 25, 25, it is usually desirable to have a "parting" member 35 between the sashes 4, 5,—preferably of bead form. Where this 30 is done, a better appearance is obtained by making the inner surface of the parting 35 flush with the inner surfaces of the two guides 25, 25,—since it likewise is a component of the exposed jamb facing 6. As shown in Fig. III, the parting-member 35 is in the form of a separate metal strip bent 35 to channel shape, and it is seated over a corresponding low parting bead 36 formed by embossment of the jamb belly 8 itself, while it is secured to the latter by screws 37 extending through said parting strip and taking 40 into the strips 31. However, the parting-member 35 may just as well consist of a bead like embossment of the jamb belly 8, similar to the bead 36, but of correspondingly 45 greater height (as hereinafter described in connection with Fig. XI). On the front surface of the parting bead 35, at the point where the ends of the meeting rails of the two sashes 4, 5 stand when both sashes are closed, may be mounted a plate 38 with upper and lower edges bevelled, as a means of assuring 50 tightness of the window at this point when closed without making the meeting rails of sufficient length to be in danger of rubbing against the parting bead 35 when the sashes 55 45 are being raised or lowered.

From Figs. II and III, especially, it will be observed that the side rail 20 of the sash 4 (and the like applies to the sash 5) is included in a very narrow and inconspicuous

slot in the facing 6, between the facing pieces 25 and parting bead 35, and that—as shown—this slot is of approximately uniform width and of considerable depth, so that access of dust and air around the side rail edge is minimized. It will also be seen that the lateral adjustability of the guide portion 26 (which forms one wall of the slot just mentioned) enables the side rail 20 to be pressed toward the parting bead 35 and its 70 side 39 (which forms the other wall of the slot) with great delicacy, so as to reduce the clearance and air passage between the parts 26 and 39 to the very minimum consistent with avoidance of friction,—or even to abolish such clearance without producing substantial pressure. The dimensions of the parts and the resilience of the guide strip 25 may be so proportioned (as shown) that the degree of tightness at this point can readily be adjusted in proper correlation with the bearing pressure on the lateral side rail flange 22.

When the upper sash 4 is closed, the up-standing front strip 12 forming the top rail 40 of the upper sash enters a groove 41 in the lintel 1, formed by upward bending of the metal of its lower wall or belly, and engages in this groove so as to make a tight joint, as shown in U. S. Letters Patent No. 709,237, to W. R. Mudd, issued September 16, 1902. Preferably, the front (outside) portion of the belly and the adjacent front flank of the lintel 1 are formed by a piece 42 of anti-corrosive metal (e. g., copper, bronze, or "keystone metal"), and the rear (inside) belly portion and flank are formed by a piece 43 of steel. The upward bent flanges of the parts 42 and 43 that form the groove sides may be brought into facial contact above the groove 41 by joggling them toward one another as shown in Fig. II. Preferably, the abutting flanges are riveted or welded securely together at 44 (or both); or they may be united to the rear of the 110 groove 41, by there overlapping the pieces 42 and 43 as shown in Fig. VII and spot-welding them securely,—the groove 41 being formed, of course, entirely in the piece 42. As shown, the bottom of the lintel 1 (comprising the pieces 42 and 43) is secured to its inverted channel-shaped top piece 45 by bending the former around the latter; if desired, it may be additionally or more securely attached by welding.

At the meeting-rails 50, 51 of the sashes 4 and 5, both strips 12 and 13 of each sash are bent or flanged over horizontal toward the other sash, to afford ample strength and lateral stiffness, and one (the rear) strip of each sash is bent up or down (as the case may be) to form a somewhat springy, resilient inclined flange 52 adapted to hook inside of—and press firmly—against the similar flange 53 on the other sash and form a

tight joint when both sashes are closed, as shown. The multi-ply meeting rails 50 and 51 are thus virtually troughs, with interlocking single-ply, resilient, inclined adjacent sides and pane-recesses formed by separation of the plies of their remote sides.

At the bottom rail 54 of the lower sash 5, the sill 3 is of multi-stepped conformation, with the steps ascending inward. The lower portions of the strips or plies 12, 13 forming the bottom rail 54 are separated a distance about equal to the tread of the intermediate step by joggling of the front strip at 55, somewhat above the lower edge of the rear strip, and the front strip extends down below the rear one a distance about equal to the rise of the intermediate step. As the lower sash 5 is lowered, therefore, the relatively independent front and rear bottom rail flanges 56 and 57 formed as just described descend past the corners 58 and 59 of adjacent steps, and may even press or wipe against them and be resiliently deflected somewhat, the lower edges of these flanges being bent and inclined laterally outward, as shown, to assist in this action. To assure still greater tightness at the sill, a yielding or resilient packing 60 (e. g., a strip of felt or of rubber) may be arranged between the flanges 56, 57 for engaging the tread of the intermediate step, and may be retained and held in place by the laterally bent edge of the rear flange 57.

For counterbalancing the sashes 4, 5, sash weights 61, 61 may be arranged in each jamb 2, preferably separated by an intervening partition 62 attached to the jamb back 10 (Fig. III). These weights 61, 61 may be connected with the side rails 20 of the sashes 4, 5, by cords or chains 63, 63 passing over sheaves 65, 65 in casings 66, 66 attached to the jamb-box bellies 8 (Fig. IV) a little below the lintel 1 and extending out through openings 67, 67 in the bellies 8. The downward extending portions of these flexible sash cables 63, 63 may be concealed behind the jamb facing 6, so as to keep them out of sight and protect them from dust and dirt. As shown, the sash cables 63 are enclosed and concealed in the hollow guide beads 25, and are attached to the retroverted portions 23 of the side rails 20 by means of hooks 68 formed of suitably notched portions of the margins 23 which extend at right angles to the rest of said portions 23 (Figs. IV and V). There is, of course, ample space for the sash cables 63 between the legs of the springs 32.

I will now describe briefly certain useful modifications of the structure shown in Figs. I to V, marking similar parts with the reference characters employed in Figs. I to V as a means of dispensing with merely repetitive description.

65 In the modified construction illustrated in

Figs. VIII, IX, and X, the jamb belly 8 is not integral with the flanks 9, 9, but is a separate piece with edges inturned to form flanges 71 that fit in grooves formed by retroversion of the inner edges of the flanks 9, 9 at 72,—the flanks 9, 9 being, as here shown, integral with the jamb-back 10. The fixed fulera for the guides 25, 25 are formed by re-retroversion of the flank edges at 73, 73. The compression springs 75 for the guides 25 are leaf springs of conventional "bow" form, and bear against similar shaped rigid brackets 76 whose ends are riveted to the jamb bellies 8 at 77. The adjusting screws 78 are flat-headed instead of round-headed like the screws 30 in Figs. I to VI, and have countersunk seats in the thickness of the guides 25 and of the springs 75, through which they extend; and they screw into threaded holes in the brackets 76. Fig. IX shows how the springs 75 may be compressed by the screws 78 in adjustment of the guides 25.

In the modification illustrated in Figs. XI and XII, the parting member or bead 80 is formed by embossment of the jamb-belly 8, as mentioned above in connection with Fig. III. Here springs are dispensed with in the mounting of the guide 25. The round-headed adjusting screws 81 take into nuts 82 welded to the jamb-belly 8 inside. The guide 25 is kept from rattling and the screws 81 are permanently secured to it (so as to be removable with it) by external flanges or collars on said screws,—in the form of washers 83 held close up against the guide 25 by cotter pins 84 extending through the screw shanks. Since the guide bead 25 need not here afford space for springs, etc., as in Figs. I and X, the jamb-belly 8 is embossed to form a low bead 85 inside the bead 25, whose fulcrum is at the reentrant corner at the root of the bead 85. Space for edgewise play of the sash 4 between the jambs 2, 2 is afforded outside of the side rails 20 by a sort of channel 86 in the jamb belly 8, between the parting bead 80 and the inner bead 85 above mentioned. If desired, springs 90 such as shown in Figs. VIII to X may be substituted for the washers and cotter pins 83 and 84, as illustrated in Fig. XIII.

The material which I ordinarily prefer to employ for the sash strips is #16 gauge bronze or keystone metal, though cold-rolled steel of the same gauge may be used if desired. For the guides 25 etc. forming the exposed facing of the jamb, I generally prefer the same materials of #12 gauge. For the sill and the front exposed portion of the bead, I prefer the same materials in about #12 or #14 gauge.

Having thus described my invention, I claim:

1. The combination of metal window

jambs; a sliding metal sash with laterally-flanged side rails and space for edgewise play outside them; and metal guides for said sash with portions extending between and engaging the lateral side rail flanges and adjustable transversely of the window, and thus controlling the edgewise position of the sash.

2. The combination of metal window-jambs; a sliding metal sash with retroverted side rails and space for edgewise play outside them; and metal guides for said sash extending between and into the retroverted portions of said side rails and engaged with their bights, and thus controlling the edgewise position of the sash.

3. The combination of opposed metal window-jambs; a sliding metal sash with retroverted side rails and space for edgewise play between said jambs; and metal facings for said jambs with guide portions extending between and into the retroverted portions of said side rails and engaged with their bights, and thus controlling the edgewise position of the sash.

4. The combination of metal window-jambs; a sliding metal sash with retroverted side rails and space for edgewise play outside them; metal guides for said sash with portions extending between and into the retroverted portions of said side rails; and means for concurrently adjusting said guide portions transversely of and in and out of the window.

5. The combination of metal window-jambs; a sliding metal sash with laterally-flanged side rails and space for edgewise play outside them; metal guides for said sash with portions extending between and engaging the lateral side rail flanges; and means for adjusting the flange engaging portion of at least one of said guides transversely of the window, and thus controlling the edgewise position of the sash comprising spring means interposed between jamb and guide, and screw means taking into threaded means on the jamb.

6. The combination of metal window-jambs; a sliding metal sash with laterally-flanged side rails and space for edgewise play outside them; metal guides for said sash with portions extending between and engaging the lateral side rail flanges; and means for adjusting the flange engaging portion of at least one of said guides transversely of the window, and thus controlling the edgewise position of the sash comprising spring means urging the guide outward from the jamb, and screw means for taking up on the guide against the resistance of said spring means.

7. The combination of metal window-jambs; a sliding metal sash with laterally-flanged side rails and space for edgewise play outside them; metal guides for said

sash with portions extending between and engaging the lateral side rail flanges; and means for adjusting the flange engaging portion of at least one of said guides transversely of the window, and thus controlling the edgewise position of the sash comprising spring means attached to the guide and removable therewith, and screws extending through the guide.

8. The combination of metal window-jambs; a sliding metal sash with retroverted side rails and space for edgewise play outside them, metal guides for said sash extending between and into the retroverted portions of said side rails and engaged therewith to control the edgewise position of the sash, spring means urging said guides outward from the jamb; and means for taking up on the guides against the resistance of said spring means.

9. The combination of metal window-jambs; a sliding metal sash with retroverted side rails and space for edgewise play outside them; guides with fixed fulcra on said jambs engaged in the retroversion grooves of said side rails at points substantially offset edgewise of the sash from said fulcra; and means adjustable to rock said guides on said fulcra and thereby control the positions of the side rails.

10. The combination of metal window-jambs; a sliding metal sash with laterally-flanged side rails and space for edgewise play outside them; and metal guides for said sash with portions extending between and engaging the lateral side rail flanges; and means for adjusting the flange engaging portion of at least one of said guides transversely of the window, and thus controlling the edgewise position of the sash comprising spring means attached to the guide and removable therewith, and screws extending through the guide.

11. The combination of a sliding metal sash with a laterally flanged side rail; a metal window jamb with facing pieces including said side rail between them, one of said facing pieces having a fixed fulcrum and engaging the lateral side rail flange at the inner side thereof substantially inside of said fulcrum; and means adjustable to rock said fulcrumed facing piece on its said fulcrum and press said side rail edgewise in the direction of said jamb and laterally toward the other facing piece.

12. The combination of opposed metal window jambs, a sliding metal sash with laterally flanged side rails and space for edgewise play between said jambs, hollow metal beads on said jambs extending between and engaging the lateral side rail flanges, and thus controlling the edgewise position of the sash, and sash cables in said beads attached to said side rails.

13. The combination of metal window

jambs; a sliding metal sash with retroverted side rails and space for edgewise play outside them; metal facings for said jambs with guide portions extending between and into the retroversion grooves of said side rails, and preventing lateral or edgewise play of the sash by engagement with the groove sides and bottoms; and sash cables enclosed in the jamb facings attached to said side rails.

14. The combination of opposed hollow metal window jambs; with sash weights therein, a sliding metal sash with retroverted side rails; hollow metal facing pieces for said jambs with portions extending between and into the retroverted portions of said side rails; and sash cables in said facing pieces attached to the retroverted portions of said side rails and connected to said sash weights.

15. The combination of a multi-stepped sill, and a sliding metal sash with bottom rail comprising flanges adapted to descend past the edges of adjacent steps and a yielding packing for engaging the tread of an intermediate step.

16. The combination of a multi-stepped sill, and a sliding metal sash with bottom rail comprising flanges adapted to descend past the edges of adjacent steps and a yielding packing between the flanges held in place by the laterally bent edge of one of them.

17. The combination of a sliding metal sash with an upstanding metal strip at its upper rail, and a sheet metal lintel composed of inside and outside plates bent upward to afford a groove for receiving said upper rail strip between them, and in facial contact above said groove.

18. The combination of a sliding metal

sash with an upstanding metal strip at its upper rail, and a sheet metal lintel composed of inside and outside plates of dissimilar metals bent upwards to afford a groove for receiving said upper rail plate between them, and secured together in facial contact above said groove.

19. In a metal window, the combination of sliding sashes with multi-ply sheet metal trough-like meeting rails, said multi-ply rails each having one of its plies outwardly joggled to afford glazing grooves, and the other ply of each meeting rail being extended beyond the first mentioned one at an inclination to form an inclined springy flange for making a tight joint with the corresponding flange of the other meeting rail.

20. The combination of opposed hollow metal window jambs with sash weights therein, a sliding metal sash with laterally-flanged side rails affording spaces for edgewise play outside them, hollow facing pieces detachably secured to said jambs with slots between them for the side rails of said sash, and sash cables attached to said side rails and connected to said sash weights.

21. The combination of a hollow metal window jamb, a sliding metal sash having laterally-flanged side rails affording spaces for edgewise play outside them, hollow facing pieces in front of said jamb with a slot between them for the said side rails of the sash, stout transverse metal strips behind the jamb front, and screws extending through said facing pieces and the jamb belly and taking into said strips.

In testimony whereof, I have hereunto signed my name at Philadelphia, Pennsylvania, this 15th day of September 1921.

JOAH BROGDEN.
